UNITED STATES PATENT OFFICE.

JOSEPH T. PRICE, OF PHILADELPHIA, PENNSYLVANIA, ASSIGNOR TO HORN SURGICAL COMPANY, OF PHILADELPHIA, PENNSYLVANIA, A CORPORATION OF PENNSYLVANIA.

KNITTING MACHINE.

Application filed June 3, 1922. Serial No. 565,506.

To all whom it may concern:

- Be it known that I, JOSEPH T. PRICE, a citizen of the United States, residing at Philadelphia, county of Philadelphia, and 5 State of Pennsylvania, have invented certain new and useful Improvements in Knitting Machines, whereof the following is a specification, reference being had to the accompanying drawings.
- 10 This invention relates to knitting machines for knitting therapeutic garments such as elastic stockings, bandages, etc., wherein the elasticity inherent in the garment is due to the presence of an elastic 15 thread which is interknitted with the body yarn as the garment is fabricated.

An object of the invention is to provide improvements in elastic thread feeding devices for machines of the character stated 20 whereby the working tension on the thread and consequently its length may be automatically varied as the knitting proceeds to produce a garment which is fashioned to conform to the contour of that portion of the 25 body upon which the garment is destined to be worn.

Another object of the invention is to provide a rib knitter embodying a pattern chain for controlling the operation of the elastic 30 thread feed, so that garments of various kinds and shapes may be knitted on the one machine by merely changing the pattern chain or the relation of its tripping elements.

A further object of the invention is to 35 provide an indicator for embodiment in a thread tensioning mechanism of the character described whereby the exact degree of tension on the thread may be observed by the operator at all times during the operation 40 of the machine.

In addition to the foregoing this invention comprehends improvements in the details of construction and arrangement of the correlated parts to be hereinafter described 45 and particularly pointed out by the appended claims.

In the drawings, Fig. I is a view in perspective of a circular rib knitting machine embodying my improved mechanism for 50 tensioning and feeding elastic thread to the knitting mechanism.

Fig. II is a view of the machine in top

plan omitting a portion of the superstructure to disclose the mechanism therebeneath.

Fig. III is a view in side elevation of the 55 lower portion of the machine illustrating the pattern mechanism.

Fig. IV is a view in perspective of the thread tensioning and laying mechanisms viewing the same from the inner side of the 60 former.

Fig. V is a view in side elevation of the thread tensioning mechanism viewing the same from the outer side.

Fig. VI is a detail view in transverse section of a speed changing pulley and power transmission element forming part of the thread tensioning mechanism. 65

Fig. VII is a detail view in transverse section taken through the aforesaid elastic 70 power transmission element.

Fig. VIII is a detail view in elevation of a relation maintaining device for insuring the proper positioning of two tripping elements forming parts of the thread tension- 75 ing mechanism.

Figs. IX and X are fragmentary views in plan and front elevation, respectively of a modified form of tension indicating mechanism. 80

Fig. XI is a detail view in side elevation of a modified means to guide the portions of the thread entering and leaving the tension rollers; and

Fig. XII is a detail fragmentary view of 85 a wear take-up means embodied in the bell crank forming part of the pattern mechanism.

With reference to the drawings, 10 indicates the base of a conventional form of circular rib knitting machine supporting the bed plate 11, the latter constituting a mounting for the stationary needle cylinder 12 and the rotating cam cylinder 13. The machine illustrated is designed to knit a ribbed fabric 90 of the two to one type, the cylinder needles, arranged in pairs being indicated at 14 in Fig. II and the dial needles at 15, so as to form in a well known manner a fabric showing double wales at one side of the fabric 95 and single wales upon the other side. The body yarn designated "a"—Fig. IV—is fed to the needles in a manner customary in rotating cam cylinder machines. During the 100

knitting of a fabric of this type, the elastic thread consisting of a very fine strand of india rubber inclosed in a casing of yarn, is laid between the cylinder needle loops and 5 dial needle loops as the loops are cast during the knitting of each course, so that the elastic thread is securely enclosed within the body of the fabric.

The elastic thread feeding mechanism is 10 carried by an arm 16 which is fixed to and extends radially from the cam cylinder, and includes a variable speed transmission mechanism consisting of a rectangular open sided frame 17 within which a pair of horizontal, 15 vertically spaced, driving and driven shafts 18 and 19 respectively are suitably journaled. The lower or driven shaft 19 is extended beyond the side of the frame 17 to support a fluted roller 20 which cooperates 20 with a similar roller 21 loosely carried upon one end of a lever 22 which is turn is fulcrumed at 23 upon the adjacent side of the frame 17. A coiled spring 24 is secured at one end to the free end of the lever 22 while 25 the opposite end of said spring is fixed to a pin extending from the side of the frame 17 so that the roller 21 will be resiliently urged into contact with the roller 20. If desired a means may be provided to vary the tension 30 of the spring 24 so that a proper degree of pressure between the rollers 20 and 21 may be secured. The fulcrum point of the lever 22, it will be observed, is located directly above the roller 20 and the length of said 35 lever is such as to cause the roller 21 to travel in a curved path which is tangential relative to the roller 20, thereby permitting the rollers 20 and 21 to coact to pinch an elastic thread fed therebetween to a degree 40 dependent upon the tension of the spring 24. Loosely mounted upon each of the shafts 18 and 19 are expansible cone pulley couples 25 and 26 respectively, each couple comprising conical members designed for shifting movement 45 toward and away from each other upon their respective shafts, the cone faces being disposed in opposed relation as shown, whereby to accommodate between them an elastic power transmission element indicated 50 generally at 27 and comprising a pair of endless helical spring elements 28 along which are strung a plurality of sections of tubular material 29, each section having a core 30 of relatively soft material such as 55 rattan protruding beyond the ends of the tubular sections and bevelled to correspond to the angle of the cone members of the pulleys 25, 26 so as to contact with the faces thereof. A pair of levers 31 and 32 are fulcrumed upon the frame 17, one upon each vertical member so that the lower ends of the levers may engage the outer surfaces of the 60 cone members of the pulley 26 while the portions of said levers above their fulcrum 65 points may engage the outer sides of the

cone members of the pulley 25 by virtue of lateral enlargements 33 formed upon said levers. A shaft 34 is journaled in brackets 35 fixed to the upper portion of the frame 17 and said shaft 34 is threaded oppositely 70 along its ends for corresponding engagement with a pair of nuts 36 and 37 to which the upper ends of the levers 31 and 32 are respectively pivotally connected. A bevelled gear 38 is fixed to one end of the shaft 34 for 75 meshing engagement with a bevelled gear 39 mounted upon the upper end of a vertical shaft 40, one end of which is journaled in one of the said brackets 35 and the opposite end journaled in an extension of the frame 80 17. A bevelled gear 41 is fixed to the lower end of the shaft 40 for meshing engagement with a bevelled gear 42 which is fixed to a short section of shaft 43 journaled in a bracket 44 extending laterally from the 85 frame 17. An actuating device or tappet wheel is mounted on the shaft 43 in the form of a plurality of radial arms 45 which are designed to be successively tripped by one or the other of a pair of tripping pins 46 and 47 mounted for shifting movement in a horizontal plane radially of the machine upon a bracket 48 which is fixed to the side of the bed plate 11 and which supports a vertical post 49 in turn supporting in pivotal relation a pair of superposed push levers 50 and 51. One end of each of said levers 50, 51 is designed to engage the end of its associated and adjacent tripping pin. A coiled spring 52 is embraced about the outer end of each pin 46 and 47 and interposed between the headed ends of said pins and the bracket 48 to retain said pins in normal retracted position; and a safety or relation maintaining device 53 is provided comprising a pair of 100 oppositely extending arms each designed to engage beneath the headed end of its respective pin 46 and 47, the device 53 being fulcrumed at a point intermediate its extremities upon the bracket 48 so that when one pin 105 is retracted the other one is extended and vice versa, except at such times when both pins 46, 47 are retracted under the influence of their individual springs 52. Each lever 50 and 51 is enlarged at its trip pin engaging 110 end as shown at 54 forming push buttons to permit said levers to be manually operated when desired. The opposite end of each lever 50 and 51 is designed to engage one arm of its associated bell crank of a pair indicated at 55 and 56 respectively, said bell cranks being fulcrumed at 57 upon the side of the base 10 while their opposite arms are 115 designed to ride over an endless chain 58 constituting a portion of the pattern mechanism. The chain 58 is operated by a sprocket wheel 59 loosely mounted upon a shaft 60, but having a frictional engagement therewith and fixed to said sprocket wheel is a 120 ratchet wheel 61 operatively associated with 125 65

a pawl 62 pivotally carried upon an arm 63 which is loosely supported upon the shaft 60. A link 64 is pivoted at one end to the extremity of the arm 63 and the opposite end 5 of said link is eccentrically pivoted to the face of a disk 65 which is in turn fixedly mounted upon a shaft 66 extending horizontally across the machine to support at its opposite end a relatively large spur gear 67 in 10 meshing engagement with a pinion 68 fixed upon the power shaft 69. A counter-balanced crank arm 70 may be fixed to the shaft 60 to effect rotation of the sprocket 59 for the purpose of effecting manual adjustment 15 of the machine. An annular gear 71 is mounted over the bed plate 11 of the machine and is immovably supported upon arms 72 extending radially and inwardly from said bed plate. A vertical shaft 73 is supported upon the frame 17 for rotation and fixed to said shaft is a spur gear 74 driven by an idler 74^a in meshing engagement with the annular gear 71. A bevel gear 75 is carried upon the upper end of the shaft 73 for meshing engagement with a bevel gear 76 which is fixed to a projecting end of the shaft 18 forming part of the variable speed drive. 20

A bracket 77 carried by the cam cylinder 13 supports the needle dial and also a pivoted container 78 in which the elastic thread is loosely held. The elastic thread, indicated at 79 is brought upwardly from the source of supply and trained over a guide member 80 and then strung across the face of a roller 81 which is fixed to the upper end of a vertical shaft 82 journaled at its lower end upon an extension of the bracket 77 and at its upper end upon a bracket arm 83 projecting laterally from a central rod 84 carried by the cam cylinder. The roller 81 is formed with a cylindrical intermediate portion covered with felt and smooth conical end portions. A gear wheel 85 is fixed to the lower end of the shaft 82 for meshing engagement with the annular gear 71. The elastic thread 79 is then trained over a second guide member 86 and after changing its direction of movement by passage over a third guide 87 positioned directly over the tensioning mechanism is led downward, through the eye of a guide member 88 and subsequently passed between the above-described fluted rollers 20 and 21 of the feeding mechanism. A stripping finger 81^a is adjustably carried by the arm 83 to engage the felted face of the roller 81 so as to strip the elastic thread from said roller and prevent the thread from being carried around with the roller by adhesion thereto. Issuing from between said fluted rollers 20, 21 the elastic thread 79 passes through the eye of another guide member 89 and finally through a guide member 90 carried by a post 91 which is fixed to the cam cylinder 13 and positioned so that the elastic thread 79 may be readily laid between the needles 14, 15 during the knitting of the fabric, in the manner described above. For the purpose of manually adjusting the variable speed drive with reference to the working tension 70 desired on the elastic thread 79 a hand wheel 92 may be fixed to the extending end of the threaded shaft 34. To afford a visual indication of the degree of tension under which the elastic thread 79 is fed I may provide 75 an indicating device consisting of a link 93 pivoted to one end of the nut 37 and having a slot 94 formed longitudinally in its opposite end to receive a pin 95 extending from the nut 36. A rack bar 96 is carried 80 by the link 93 for meshing engagement with a pinion 97 carried upon a shaft 98 which is journaled in a dial plate 99 and carries a pointer 100 designed to travel over a series of graduations 101 provided upon the dial 85 plate.

When knitting a garment on this machine a normal tension should be imparted to the elastic thread 79 by manipulation of the hand wheel 92 so that when knitting the 90 full portions of the garment, equal in diameter to that of the needle cylinder, the tension on the thread will be at a minimum, but of a degree sufficient to insure proper formation of the garment. As the knitting 95 proceeds the pattern chain 58 will be shifted intermittently under the pawling influence of the shaft 66 transmitted through the link 64 and pawl 62 until a series of lugs 102 carried upon the chain along its outer edge 100 will be successively brought beneath the arm of the bell crank 55, thereby rocking the same so as to shift the tripping pin 46 inward and simultaneously shifting the pin 47 outwardly. During each rotation of the 105 cam cylinder 13 one of the arms 45 will be tripped by the pin 46, thereby rotating the shaft 43 in a counterclockwise direction, the motion of which is transmitted through its associated train of gears to the shaft 34, 110 corresponding rotation of which effects a separation of the nuts 37 and 36 so that the upper ends of the levers 31 and 32 are moved apart and their lower ends moved toward each other, thus moving together the cone 115 members of the pulley 26 so as to enlarge the circumferential line of contact between the cone faces and the edges of the transmission element 27, and to correspondingly decrease the circumferential line of contact between 120 said power element and the faces of the cone members of the pulley 25. As a consequence the speed ratio between the shafts 18 and 19 will be altered so as to decrease the speed of the driven shaft 19. The rate 125 at which the elastic thread 79 is fed by the fluted roller 20 will thus be slightly less than the rate at which it is taken up during rotation of the cam cylinder 13, and consequently the thread will be slightly ten- 130

sioned. The next lug of the series 102 to engage the bell crank 55 will cause a repetition of this performance resulting in another tensioning of the elastic thread 79 and so on until the garment is gradually narrowed to the point desired. Obviously, it will be necessary to effect a reversal of the process described above to cause a uniform slackening of the elastic thread 79 to permit widening of the garment if such widening is required in the form of the garment. This reversal is effected by the provision of a series of lugs 103 located along the inner edge of the chain 58 so as to engage the end of the bell crank 56. As soon as this bell crank 56 is engaged the lower lever 51 is rocked causing the lower tripping pin 47 to be extended and the upper pin 46 retracted so that during each revolution of the cam cylinder 13 the arms 45 will be tripped along their lower ends and cause rotation of the shaft 43 in a clockwise direction. As a consequence the speed of the fluted roller 20 will be stepped up with reference to the reduced rate of feed of the elastic thread 79 and the tension on said thread will be thus uniformly decreased as each lug 103 of the series is brought beneath the bell crank 56, and so on until the required degree of tension is relieved.

It is desirable in order to insure perfect working of the tensioning mechanism described to prevent tension upon any portion of the elastic thread 79 except between the fluted roller 20 and the point of laying in of said thread. To this end the roller 81 is provided, the function of which is to unravel and raise the thread 79 from the supply within the container 78 and to maintain slack within the elastic thread at every point up to the roller 20. The size of the gear 85 is therefore proportioned with respect to the size of the gear 71 so as to maintain the proper degree of slack during operation of the machine. The rate of feed of the roller 81 is therefore arranged so as to be in step with the take-up of the needle cylinder 12 when the latter is knitting the wider portions of the garment requiring a maximum rate of thread supply. Obviously, when the machine is knitting the narrow portion of the garment the rate of feed of the roller 81 being the same at all times the thread would be supplied faster than required were it not for the provision of the conical lower end of the roller 81. Thus as the rate of take-up of the needle cylinder 12 decreases the elastic thread 79 will sag between the guides 80 and 86 and fall away from engagement with the roller 81 and feeding of said thread will cease until the thread is again raised into contact with the roller by take-up of the knitting mechanism. The effect of this arrangement there-

fore is to provide an intermittent feed of the elastic thread 79 and also to accommodate periods of release or slack in the thread. It will be noted that as the nuts 36 and 37 are shifted relatively resulting in a tensioning or slackening of the elastic thread 79 their movements will be imparted to the pointer 100 so that the position thereof with respect to the graduations 101 will indicate the exact degree of tension or strain under which said elastic thread is fed to the needles 14, 15.

In Figs. IX and X, I have illustrated a modified form of mechanism for indicating elastic thread tension which operates upon the same principle as the mechanism hereinbefore described but embodies a more efficient construction. The rack bar 96' is secured to the upper side of the nut 37 and slides over the nut 36. A shaft 98' is journalled at one end in the dial plate 99 and at its other end in a bracket 104 fixed to the frame 17. A pinion 105 carried by the shaft 98' meshes with the rack bar 96', and the former carries the pointer 100. By supporting the shaft 98' at both ends a more rigid construction is provided ensuring a more accurate indication of thread tension.

In lieu of the thread guides 88 and 89 for the feed rollers 20, 21, I may employ as an alternate construction the type of guides shown in Fig. XI wherein 106 indicates a funnel shaped guide carried upon a bracket 107 so as to be positioned with its smaller end directed toward the point of contact of the rollers 20 and 21 and in closely spaced relation at the entering side. A second funnular guide 108 carried by a bracket 109 is positioned at the leaving side of the rollers 20, 21 with its larger end directed toward said rollers and bevelled so as to be located in very closely spaced relation thereto. The axes of the two funnular guides 106, 108 are also placed in direct alignment. Thus by inserting the end of the elastic thread 79 into the funnel guide 106 the point of said thread is automatically guided between the rollers 20, 21 and upon issuing at the other side is received into the funnel guide 108 and issued therefrom so as to be readily grasped for adjustment in the needle cylinder feed.

The lugs 102 and 103 of the pattern chain are subject to wear and as a slight decrease in height will result in magnified alteration of the extent of movement of the tripping pins 46 and 47 by reason of the multiplying lever connections intervening, I may provide a compensating device such as is shown in Fig. XII, wherein the upper ends of the bell cranks 55 and 56 are each provided with a finger 110 mounted thereon in pivotal relation and having a lateral extension 111 adapted to engage the

end of the associated bell crank 50 or 51. A set screw 112 threaded into the bell crank 55 or 56 and bearing against the extension 111 serves to vary the effective length of the said bell crank to offset any wear of the pattern chain lugs 102, 103.

Thus it will be seen that while the body yarn *a* may be fed to the needles 14, 15 in a uniform manner so that the fabric product would ordinarily be a straight sided tube, nevertheless a fashioned garment is actually produced because of the variable tension imparted to said elastic thread, during the knitting of different parts of the garment. Thus, while knitting a portion of the garment having the full diameter of the needle cylinder 12 the tension on the elastic thread 79 must be at a minimum, and when an extremely narrow portion is to be knitted the elastic thread 79 must be tensioned to a relatively high degree, so that when the garment is finished the tensioned portion of said elastic thread will cause a shrinking or reduction in diameter of the parts of the garment enclosed by the tensioned thread. By arranging the lugs 102, 103 on the pattern chain 58 a garment of any desired form may be made, having one or more narrow portions and shaped with either gradual or abrupt curves according to the contour of those portions of the body to be covered. The shape of the garment may be altered at will independently of the pattern mechanism by manually pushing in one or the other of the levers 50 and 51 as the knitting proceeds. As the working tension of the elastic thread 79 is indicated by the indicating mechanism 100, 101 described the operator is apprised at every moment of the true working conditions of the machine, even when positioned at a distance therefrom, so as to effect adjustments when needed with a minimum loss of time.

Obviously, during the passage of blank portions of the pattern chain 58 beneath the bell cranks 55, 56, the feed mechanism is ineffective to cause any variation in tension on the elastic thread 79 and consequently straight tubular work will result, the tripping pins 46 and 47 being maintained in neutral positions. Should pressure be accidentally applied to the push levers 50 and 51 simultaneously the safety or relation maintaining device 53 will function to prevent the extension of more than one tripping pin 46 or 47 into the path of motion of the tappet wheel 45 and in this manner injury to the machine is prevented.

Having thus described my invention, I claim:

1. In a circular rib knitting machine, the combination of means for feeding an elastic thread under tension to the knitting mechanism and means for feeding said elastic

thread from a source of supply to the first feeding means whereby to slack the elastic thread at every point in its course between the first and second feeds.

2. In a circular rib knitting machine, the combination of means for feeding an elastic thread under tension to the knitting mechanism and a roller around which the elastic thread is passed at a point between the source of supply and said feeding mechanism whereby to automatically slack said elastic thread at all points between the roller and said feeding mechanism.

3. In a circular rib knitting machine, including a rotary cam cylinder, means carried by the cam cylinder for feeding an elastic thread under tension to the knitting mechanism, a roller around which the thread is passed to feed the thread from a source of supply to said feeding mechanism with accommodation for periods of release therein, a stationary gear, and a pinion in mesh with said gear and carried by the cam cylinder for operating said roller.

4. In a circular rib knitting machine, including a rotary cam cylinder, the combination of means for feeding an elastic thread under tension to the knitting mechanism, a container movable with the cam cylinder adapted to contain a supply of elastic thread, a series of guides for conveying the elastic thread from the source of supply to said feeding mechanism, a roller having a cylindrical intermediate and conical end portions located between said guides and engaging the thread to feed the thread without tension to said feeding mechanism, a stationary gear, and a pinion carried by the cam cylinder and meshing with said gear to operate the roller.

5. In a circular rib knitting machine, the combination of a driven roller for feeding an elastic thread to the knitting machine, a lever, a second roller carried by one end of said fulcrumed lever with capacity for movement toward and away from the driven roller in a direction substantially tangential thereto, and a spring connected to the opposite end of the lever to urge the second roller into engagement with the driven roller so as to pinch the elastic thread therebetween.

6. In a circular rib knitting machine, the combination of a speed changing device including a driving and a driven shaft, an elastic transmission, companion rollers—one of which is tangentially influenced—operable by the driven shaft to feed an elastic thread to the knitting mechanism, a pattern mechanism, and a tripping means operable at a point during each course operation of the machine to vary the speed ratio between the driving and driven shafts to vary the rate of feed of the thread.

7. In a circular rib knitting machine, the

- combination of a speed changing device including a driving and a driven shaft, an elastic connecting transmission, companion rollers—one of which is tangentially influenced—operable by the driven shaft to feed an elastic thread to the knitting mechanism, a pattern mechanism, and a pair of tripping means operable alternately by the pattern mechanism to control operation of the speed changing mechanism to vary the speed ratio between the driving and driven shafts to effect a variation in the rate of feed of the elastic thread.
8. In a circular rib knitting machine, the combination of a speed changing mechanism including a driving and a driven shaft, means operable by the driven shaft to feed an elastic thread to the knitting mechanism, an expandible cone pulley carried by each shaft, a power transmission element connecting the pulleys, a pattern mechanism, and means operable by the pattern mechanism to alter the relation of said cone pulleys to effect a change of speed between the driving and driven shafts to effect a variation in the rate of feed of the elastic thread.
9. In a circular rib knitting machine, the combination of a speed changing mechanism, including a driving and a driven shaft, means operated by the driven shaft to feed an elastic thread to the knitting mechanism, an expandible cone pulley mounted on each shaft, a power transmission element operatively connecting said pulleys, a shaft having oppositely threaded portions, a pattern mechanism including means operable upon said threaded shaft to rotate the same alternately in one direction or the other, and means operable by said threaded shaft to vary the relation of the pulleys to effect a change in speed ratio between the driving and driven shaft to change the rate of feed of the elastic thread.
10. In a circular rib knitting machine, the combination of companion fluted rollers,—one of which is tangentially influenced for feeding an elastic thread to the knitting mechanism, means for varying the rate of feed, a tappet member for controlling said feed varying means, a pattern mechanism, a pair of tripping pins, means normally retaining the tripping pins in retracted position, and bell cranks operable by the pattern mechanism for throwing one or the other of said tripping pins into a position for engagement with the tappet member to effect variation in the rate of feed of the elastic thread.
11. In a circular rib knitting machine, the combination of means for variably feeding an elastic thread to the knitting mechanism, a tappet member for controlling operation of said mechanism, a pattern mechanism, a pair of tripping members, means normally retracting said tripping members, a manu-
- ally operable means for each tripping member to extend the same into engageable position with respect to the tappet member, a pattern mechanism, and bell cranks operable by said pattern mechanism through 70 said manually operable means as instrumentalities to automatically extend the pins in the manner stated to effect a variation in the rate of feed of the elastic thread.
12. In a circular rib knitting machine, the combination of means for variably feeding an elastic thread to the knitting mechanism, a tappet means for controlling operation of said feed, a pattern mechanism, a pair of tripping members, means operable by the 80 pattern mechanism to dispose either of said tripping members into engagement with the tappet member, and a relation retaining member correlating said tripping members to maintain the same in alternately retracted 85 or extended position.
13. In a circular rib knitting machine, the combination of means for feeding an elastic thread to the knitting mechanism, means for varying the tension upon the thread, a 90 dial plate, a pointer traveling over the dial, and a rack and pinion operated by the feeding mechanism to move the pointer and cause the latter to indicate the speed of the aforesaid feeding means whereby the 95 exact degree of tension upon the elastic thread may be observed.
14. In a circular rib knitting machine, driven and tangentially influence companion rollers for feeding an elastic thread to the 100 knitting mechanism, a variable speed means to control and vary the rate of feed, and pattern mechanism including independent operable bell cranks cooperating with the feed control, one to effect increase in the 105 rate of feed and another to effect decrease in the rate of feed.
15. In a circular rib knitting machine, means for feeding an elastic thread to the 110 knitting mechanism, means to control and vary the rate of feed, and a pair of superposed push levers capable of manual operation, actuatable at will to effect respectively increase or decrease in the rate of feed, whereby to manually control the fashioning 115 of a garment.
16. In a circular rib knitting machine, means for feeding an elastic thread to the 120 knitting mechanism, means to control and vary the rate of feed, a pair of superposed push levers capable of independent manual operation, actuatable respectively to effect increase and decrease in the rate of feed, and a relation maintaining device correlating the manually operable means to prevent operative manipulation thereof of more than one at a time.
17. In a circular rib knitting machine, means for variably feeding an elastic thread 125 to the knitting mechanism, and means for 130

feeding the thread to the first feeding means at a variable rate in step with the take-up of said first feed.

18. In a circular rib knitting machine, means for variably feeding an elastic thread to the knitting mechanism, means for feeding the thread to the first feeding means, including a roller and thread guides co-operating to retain the thread in frictional contact with the roller, whereby the thread may fall away from the roller when the rate of feed of the latter is excessive with respect to the rate of take-up of the first feed, to maintain the rate of thread supply in step with the rate of take-up.

19. In a circular rib knitting machine, means for variably feeding an elastic thread to the knitting mechanism, and means for feeding the thread to the first feed including a roller turning about a substantially vertical axis, thread guides to retain the thread in frictional engagement with a portion of the circumference of the roller, and a conical portion at the lower end of the roller permitting the thread to sag away from contact with the roller and to guide the thread back into contact.

20. In a circular rib knitting machine, means for feeding an elastic thread to the knitting mechanism comprising a roller having a cylindrical intermediate section covered with a felt facing and smooth conical end portions, and guides to retain the

thread in engagement with a relatively small portion of the circumference of said roller.

21. In a circular rib knitting machine, means for feeding an elastic thread to the knitting mechanism comprising a roller having a cylindrical intermediate section covered with a felt facing and smooth conical end portions, guides to retain the thread in contact with only a small portion of the circumference of the roller, and an adjustable stripping finger to prevent the thread from being carried around the roller by adhesion with the felt facing.

22. In a circular rib knitting machine, means to feed an elastic thread, means to vary the rate of feed, a pattern mechanism including a pattern chain carrying pattern lugs, bell cranks operable by engagement with the lugs to multiply motion and transmit the same to the varying means, and adjustable pivoted fingers on the lug-engaging ends of said bell cranks for maintaining uniform the rate of multiplication of movement by compensating for wear of the pattern lugs.

In testimony whereof, I have hereunto signed my name at Philadelphia, Pennsylvania, this 29th day of May 1922.

JOSEPH T. PRICE.

Witnesses:

JAMES H. BELL,
E. L. FULLERTON.
